The Hydraulic Development Corporation, Inc.,
Mount Gilead, Ohio, a corporation of Delaware

Application September 3, 1940, Serial No. 94,768

Term of patent 7 years

To all whom it may concern:

Be it known that I, Johan A. Muller, a citizen of the United States, residing at Mount Gilead, in the county of Morrow and State of Ohio, have invented a new, original, and ornamental Design for a Press, of which the following is a specification, reference being had to the accompanying drawing, forming part thereof, wherein:

Figure 1 represents a front elevational view of a press illustrating my new design;

Figure 2 is a side elevational view thereof;
Figure 3 is a perspective view thereof; and
Figure 4 is a top plan view thereof.

I claim:

The ornamental design for a press, substantially as shown.

JOHAN A. MULLER.
